UNITED STATES PATENT OFFICE.

ARTHUR PEYTON BASHAM, OF OWENSBORO, KENTUCKY, ASSIGNOR TO TANDY L.
HARL, OF OWENSBORO, KENTUCKY.

CONCRETE POST.

1,187,600.

Specification of Letters Patent. Patented June 20, 1916.

Application filed November 16, 1914. Serial No. 872,432.

To all whom it may concern:

Be it known that I, ARTHUR P. BASHAM, a citizen of the United States, residing at Owensboro, in the county of Daviess and 5 State of Kentucky, have invented a new and useful Concrete Post, of which the following is a specification.

One object of the present invention is to provide novel means whereby a fastening 10 device, such as a staple or a nail, will be deflected by direct contact with a concrete body within the contour of a fastening binder embedded directly in the body.

Another object of the invention is to im- 15 prove the construction of the binder.

It is within the scope of the disclosure to improve generally and to enhance the utility of devices of that type to which the present invention appertains.

20 With the above and other objects in view which will appear as the description pro- ceeds, the invention resides in the combina- tion and arrangement of parts and in the details of construction hereinafter described 25 and claimed, it being understood that changes in the precise embodiment of the invention herein disclosed can be made within the scope of what is claimed without de- parting from the spirit of the invention.

30 In the accompanying drawing: Figure 1 shows in front elevation, one form of the invention; Fig. 2 is a section on the line 2—2 of Fig. 1; Fig. 3 is a section taken on the line 2—2 of Fig. 1, but showing the fasten- 35 ing element and the part held thereby as added details; Fig. 4 is an elevation show- ing a modified form of the invention; Fig. 5 is a section on the line 5—5 of Fig. 4; Fig. 6 is a section on the line 6—6 of Fig. 4.

40 In carrying out the invention, and refer- ring specifically to Figs. 1, 2 and 3, there is provided a concrete body 1. Embedded di- rectly in the concrete body 1 is a fastening binder 2 in the form of a strip. The fas- 45 tening binder 2 is curved transversely as shown at 3, so that a portion of the binder is disposed out of parallelism with respect to one exterior face 4 of the body, whereby the binder contacting part 5 of the body

50 will act as a fastening deflector co-oper- ating with the binder. As shown at 6, the concrete body 1 is extended across the for- ward edge of the binder. Fastening receiv- 55 ing openings 7 and 8 are formed in the body and are disposed opposite to the binder 2.

The openings may be of circular form, as shown at 7, or they may be elongated as shown at 8. The material which is assem- bled with the concrete body is shown at 9 and through the material 9 passes a fastener 60 which may be a nail, the fastener being de- noted by the numeral 10. The fastener 10 passes into the opening 7, engages the binder contacting part 5 of the body and is de- flected thereby into the binder as shown 65 at 11.

In Figs. 4, 5 and 6 of the drawing, there is shown a concrete body 12 in which a fastening binder 14 is directly embedded. The fastening binder 14 is in the form of 70 an angle member and the flanges of this angle member are disposed out of parallelism with one exterior face 15 of the body 12 whereby the binder contacting parts 16 of the body will act as a fastening deflector co- 75 operating with the binder. As shown at 19, the concrete body 12 is extended across the forward edge of the binder 14. In the body 12 openings 17 are formed, the openings 17 being disposed opposite to the binder 14. 80 The openings 17 lie upon opposite sides of the line 18 representing the angular forward edge of the binder defined by the diverging flanges thereof. The openings 17 further, preferably lie upon opposite sides of a line 85 extended at right angles to the edge 18.

The fastener 20 may be in the form of a staple straddled across a wire 21, the legs of the staple entering the openings 17 and being deflected by the binder contacting 90 parts 16 of the concrete body 12 into the fastener 20.

In all forms of the invention, the binder, represented by the element 2 in the one instance and by the element 14 in the other 95 instance is penetrable and preferably is fashioned from tarred paper. Although a ma- terial other than tarred paper may be used, tarred paper will be found peculiarly effi- cient. It does not rust; it does not absorb 100 the moisture out of the concrete; it does not rust the fastener; and it retains a firm hold on the fastener.

The binder is embedded in the concrete body at the time the latter is made and 105 serves to shape the reflecting elements where- by the fasteners are turned or clenched into the binder. It is to be observed that this clenching of the fastening elements is not brought about by a separate element in- 110

serted into the concrete body but is brought about by shaping the concrete body itself to bend or clench the fastening elements.

Having thus described the invention what is claimed is:—

- 5 1. In a device of the class described, a concrete body; and a penetrable fastening binder embedded directly in the body, a portion of the binder being disposed out of parallelism with respect to one exterior face of the body whereby the binder contacting part of the body will act as a fastening deflector coöperating with the binder, the concrete body being extended across the forward edge of the binder, and there being a fastening receiving opening in the body and disposed opposite to the binder.
- 10 2. In a device of the class described, a concrete body; and a penetrable fastening binder embedded directly in the body, a portion of the binder being disposed out of parallelism with respect to one exterior face of the body whereby the binder contacting part of the concrete body will act as a fastening deflector coöperating with the binder; the binder being fashioned from tarred paper, the body being provided with a fastening receiving opening coöperating with the binder.
- 15
- 20
- 25

3. In a device of the class described, a concrete body; and a penetrable binder embedded in the body, the binder being in the form of an angle member embodying flanges defining an edge, that portion of the body which lies in front of the flanges being provided with fastening receiving openings co-acting with the flanges and located upon opposite sides of said edge.

4. In a device of the class described, a concrete body and a penetrable binder embedded in the body, the binder being in the form of an angle member embodying flanges defining an edge, that portion of the body which lies in front of the flanges being provided with fastening receiving openings co-acting with the flanges, the openings being located on opposite sides of said edge, and upon opposite sides of a line at right angles to said edge.

In testimony that I claim the foregoing as my own, I have hereto affixed my signature in the presence of two witnesses.

ARTHUR PEYTON BASHAM.
